Frank A. Cutler,
ATTORNEY.

UNITED STATES PATENT OFFICE.

WALTER F. FREEMAN, OF SPRINGFIELD, MASSACHUSETTS.

TROLLEY-SHOE.

1,383,797.

Specification of Letters Patent.

Patented July 5, 1921.

Original application filed March 5, 1921, Serial No. 449,681. Divided and this application filed April 15, 1921. Serial No. 461,520.

To all whom it may concern:

Be it known that I, WALTER F. FREEMAN, a citizen of the United States of America, and a resident of Springfield, in the county of Hampden and State of Massachusetts, have invented a new and useful Trolley-Shoe, of which the following is a specification.

My invention relates to improvements in followers or shoes with which the upper ends of trolley poles are or may be equipped, the same being a divisional part of my application for Letters Patent of the United States, filed March 5, 1921, Serial No. 449,681, and consists essentially of a body which is adapted to be mounted on the axle of either a trolley-pole harp or a trolley-harp extension, and a separable and removable runner secured to said body by means of the axle upon which the latter is mounted, together with such other parts and members as may be necessary or desirable in order to render the device complete in every respect, all as hereinafter set forth.

Although this device is herein termed a shoe, by which is understood a device primarily intended to be substituted for a trolley wheel to run on an overhead trolley wire, the same may serve in the capacity of a scraper for removing snow and ice from such wire.

The shoe is designed to be mounted to rock on its axial support.

It is customary to mount a shoe of this character in a harp that is attached at the upper end of a trolley pole, or in an extension of such a harp, which pole is caused to assume an approximately erect or upright position by means of springs, so that said shoe is held against the overhead wire, in which location the shoe follows said wire as said pole moves with the car. It will be seen, therefore, that the wire-engaging parts of the shoe must necessarily wear out in a comparatively short time, so that the ordinary shoe has to be discarded and a new one substituted therefor. This renders the use of trolley shoes expensive, and the primary object of my invention is to reduce such expense by providing a comparatively simple trolley shoe, that can be mounted, like the shoes in common use, in the ordinary harp or any harp or harp extension, in place of the wheel which such harp or extension is capable of carrying, but which is constructed

in sections so that only the wire-engaging part, when worn out, need be discarded.

Another object of my invention is to provide a strong and durable shoe of this character with convenient and efficient means for holding the separable parts together, and for releasing them, when the wire-engaging part becomes worn to an extent that renders further use undesirable, so that a new part can be readily substituted for the worn part; the axial member or axle, upon which this shoe is mounted, being utilized as the lock for the removable part, it is a very simple matter to engage and disengage the separable elements.

Other objects and advantages will appear in the course of the following description.

I attain the objects and secure the advantages of my invention by the means illustrated in the accompanying drawings, in which—

Figure 1 is a top plan of a shoe which embodies a practical form of my invention, such shoe being represented as mounted in the bifurcated portion of a trolley-pole harp or trolley-harp extension; Fig. 2, a side elevation of said shoe, with a fragment of one of the arms of said bifurcated portion; Fig. 3, a rear elevation of said shoe; Fig. 4, a side elevation of the shoe runner, and, Fig. 5, a central longitudinal vertical section through the permanent part or body of the shoe, into which and with which said runner is adapted to fit and to be securely connected, and from which it may be disconnected and removed.

Similar reference characters designate similar parts throughout the several views.

In Fig. 1, I represent at 1 the bifurcated or forked portion of a trolley-pole harp, or a trolley-harp extension, with either of which my shoe is adapted to be used without distinction. The member 1 is provided with a pair of arms 2 as usual, and at the outer ends of such arms are bearings 3—3 for an axle 4. One of the arms 2 and the axle 4 appear also in Fig. 2. The axle 4 is adapted usually to carry either a trolley wheel or a trolley shoe, being utilized for the latter in the present instance.

This shoe comprises a body 5 and a removable runner 6.

The body 5 has a generally triangular superficial outline, is provided at the bottom with a pair of laterally-extending lugs 7, 110

and at the top with another pair of laterally-extending lugs 8, and has a transverse opening or bore 9 therethrough to receive the axle 4, a vertical slot 10 therethrough, 5 and a horizontal groove 11 therein. The bore 9 is back of or behind the transverse vertical center of the body 5, and the rear half of said opening communicates with the forward portion of the slot 10 intermediate 10 of the ends of said slot. In other words, the bore 9 and the slot 10 are in open communication with each other. The lugs 7 are in and behind the vertical, transverse, central plane of the body 5, while the lugs 15 8 are forward of such plane. The groove 11 is in the longitudinal center of the top of the body 5. The body 5 is of a thickness which enables it to be received between the arms 2 and the bearings 3, and 20 said body may be provided at the ends of the bore 9 with annular projections 12—12 which convert this intermediate or generally central portion of the body, wherein is located said bore, into a hub. 25 The runner 6 has on the bottom thereof in the longitudinal center a rib 13, which is adapted to fit into the groove 11 in the top of the body 5, to assist in properly locating said runner on said body, and to 30 prevent the former from moving or twisting laterally on the latter; and said runner also has on the bottom in the longitudinal center thereof, at a point nearer the rear than the front end, a downwardly-extending 35 tongue 14, which is receivable in the slot 10, and has a semi-circular recess 15 in the front edge thereof. The recess 15 has the same radius as that of the bore 9, and coincides with the corresponding portion of said 40 bore, when said tongue is introduced to its full length in said slot. The runner 6 is provided on top with a pair of guide wings 16, as is customary, the overhead trolley wire being received between said wings and in 45 the bottom of the groove formed thereby.

The runner 6 is united with the body 5 by introducing the tongue 14 into the slot 10 from above, and thrusting said tongue downwardly until the rib 13 enters the 50 groove 11 and the bottom of said runner comes to rest on the top of said body. It is necessary, of course, that the tongue 14 be inserted in the slot 10 in such a manner as properly to position the runner 6 relative to the body 5 and the recess 15 relative to the bore 9. The runner 6 is now firmly seated on the body 5, and the recess 55 15 is in exact registry with the bore 9, so that the shoe is ready to be received between the bearings 3 and to be mounted on the axle 4.

When the body 5 is properly introduced between the arms 2 of the member 1, with the hub of said body between the bearings 60 3 of said arms, each of the latter is be-

tween the lugs 7 and 8 on the corresponding side of said body, said arms having a downward and forward direction under normal conditions. The axle 4 is thrust through the bearings 3 and the bore 9 and 70 recess 15, it being remembered that said recess is now in exact alinement with the corresponding portion of said bore. The tongue 14 is thus locked in place in the slot 10 by the axle 4, so that the runner 6 is held securely in position on the body 5, and any movement of said runner independently of said body is prevented by said axle and the parts engaged thereby, and by the rib 13 and the grooved part 11 of the body. Thus 75 it is seen that the runner 6 is locked to the body 5, and the latter is mounted in position for use, by and through the medium of the axle 4.

The lugs 7, being below the arms 2, limit 80 the amount of movement which it is possible for the shoe to have on the axle 4 in one direction, and the lugs 8, being above said arms, limit the amount of movement of said shoe on said axle in the other direction. 90 The lugs 8 in the present example are at the top of the body 5 and parallel with said top.

Upon withdrawing the axle 4, the shoe 95 is released from the member 1 and can be removed therefrom, and the runner 6 is unlocked and may be lifted out of engagement with the body 5 and taken therefrom.

The body 5 may be cut away in each side 100 adjacent to the forward arcuate edge thereof, as represented at 17 in Fig. 2, for the purpose of lightening said body and saving material.

By constructing the shoe in two parts I am able to remove and replace the runner 6, 105 and substitute another therefor, with the utmost facility, wherefore a great saving is effected, as hereinbefore pointed out and can readily be understood.

It has not been deemed necessary to show 110 in the drawings either the trolley pole or the overhead trolley wire to which reference has been made, inasmuch as they are so old and well known.

The term axle as herein employed is intended to include and cover any axial or pivotal connection between the shoe and its support, provided the same be capable of locking together the runner and body of the shoe, while at the same time supporting the 120 shoe or serving as an axle therefor.

The lugs 7 and 8 permit the shoe to rock on its axle to whatever extent may be necessary to enable the shoe to accommodate itself to the vertical undulations in the overhead 125 wire, and slide beneath such wire to the best advantage and with the least liability of leaving the same, and at the same time said lugs prevent said shoe from turning completely over or rocking on said axle to an 130

extent, when out of contact with said wire, that would interfere with the engagement of the shoe with the wire or decrease the facility with which such engagement could be 5 brought about.

Provision is made in this shoe for affording a good and sufficient contact with the overhead wire. If it be desired to use a shoe having some specially designed wire-engaging part, as may be the case when the shoe is employed as an ice scraper, it is simply necessary to withdraw the axle 4, remove the body 5 from between the bearings 3, take off the old runner 6 and replace it with the new 10 runner, and return said body to its position between said bearings and reinsert said axle.

15 Cotter-pins may be employed to retain the axle 4 in place in the bearings 3, there being one such pin at each end of said axle. One 20 of these cotter-pins appears at 18 in Figs. 1 and 2.

More or less change in the size, shape, construction, and arrangement of some or all of the parts of this invention may be made, 25 without departing from the nature thereof or exceeding the scope of what is claimed.

What I claim as my invention, and desire to secure by Letters Patent, is—

1. As an improved article of manufacture, 30 a trolley shoe comprising separable sections, adapted to be mounted on the axle, of a trolley-pole harp, and removable means to secure such sections together.

2. As an improved article of manufacture, 35 a trolley shoe comprising a body adapted to be mounted on the axle of a trolley pole harp, and a separable runner mounted on said body, said runner having wings at the sides.

40 3. As an improved article of manufacture, a trolley shoe comprising a body adapted to be mounted on an axle, and a separable runner adapted to be secured to said body by means of said axle.

45 4. As an improved article of manufacture, a trolley shoe comprising a body adapted to be mounted on the axle of a trolley pole harp, and having lugs to limit the movement of said body on said axle relative to said

harp, and a separable runner adapted to be 50 secured to said body by means of said axle.

5. The combination, in a trolley shoe, with a body bored to receive an axle, and slotted to receive a tongue, of a runner provided with a tongue to enter the slot in said body, 55 said tongue being recessed to receive said axle when the tongue is in place and the axle is in the bore in said body.

6. The combination, in a trolley shoe, with a body bored to receive an axle, and slotted 60 to receive a tongue, of a runner provided with a tongue to enter the slot in said shoe, which tongue is recessed to receive said axle when said tongue is in place and the axle is in the bore in said shoe, contiguous surfaces 65 of the shoe and runner having interengaging grooved and ribbed parts.

7. The combination, in a trolley shoe, with a body bored to receive an axle, and slotted to receive a tongue, of a runner provided 70 with a tongue to enter the slot in said body, said tongue being recessed to receive said axle when the tongue is in place and the axle is in the bore in said body, contiguous surfaces of the body and runner having interengaging 75 grooved and ribbed parts, and said body being provided with lugs to limit the movement thereof on said axle relative to the supporting members for said axle.

8. The combination, with a bifurcated 80 trolley-pole member, provided with an axle, of a shoe mounted on said axle, said shoe comprising a body which is bored, to receive said axle, and slotted, the bore and slot therein intersecting, and a runner having a 85 recessed tongue to enter said slot and be engaged by said axle.

9. The combination, with a bifurcated trolley-pole member provided with an axle, 90 of a shoe adapted to be mounted on said axle, said shoe comprising a body and a runner, the latter being separable from the former and held in place thereon by said axle.

WALTER F. FREEMAN.
